G. C. SHARPE.
FENCE POST.
APPLICATION FILED SEPT. 1, 1916.

1,263,132.

Patented Apr. 16, 1918.

Inventor:
George C. Sharpe
By
John Jaywell
Attorney.

UNITED STATES PATENT OFFICE.

GEORGE C. SHARPE, OF COLUMBUS, OHIO.

FENCE-POST.

1,263,132.

Specification of Letters Patent. Patented Apr. 16, 1918.

Application filed September 1, 1916. Serial No. 116,053.

To all whom it may concern:

Be it known that I, GEORGE C. SHARPE, a citizen of the United States, resident of Columbus, county of Franklin, and State 5 of Ohio, have invented new and useful Improvements in Fence-Posts, of which the following is a specification, the principle of the invention being herein explained and the best mode in which I have contemplated 10 applying that principle, so as to distinguish it from other inventions.

My invention relates to fence posts and particularly to such posts as are formed out of metallic pipe such as gas or water pipe, 15 of such a construction that they may be set without any extraneous holding means such as a concrete foundation, etc., and yet be firmly embedded in the earth or other post foundation. Particularly, my improved 20 post is adaptable for fencing along railroad rights-of-way.

The annexed drawing and the following description set forth in detail certain means embodied in my invention, such disclosures 25 constituting but one of the various ways by which the principles of my invention may be exemplified.

In said annexed drawing:

Figure 1 represents a broken central longitudinal section of a portion of metallic pipe to be formed into my improved fence post, after one end of the same has been reamed out, as hereinafter fully explained; Fig. 2 is a bottom plan view of the portion 35 of pipe shown in Fig. 1, after the same has been subjected to a further operation, viz., slitting same into a plurality of separable members; Fig. 3 represents a broken central longitudinal section of a post, taken in 40 the plane represented by the line 3—3, Fig. 4, after the same has been set in the earth or other post foundation; Fig. 4 represents a transverse section taken in the plane indicated by the line 4—4, Fig. 3; and Fig. 5 45 represents an elevation of a conventional fence in which my improved posts have been used.

Referring to the drawing, the body of my improved fence post is represented by 1, 50 being a section cut the desired length from metallic pipe such as water or gas pipe.

One end of this section of pipe is reamed out on a long bevel, as plainly shown in Fig. 1, to form an inner beveled surface 2 of some considerable depth thus forming a 55 cutting or chisel edge 3. It will be noted that the formation of such inner beveled surface 2 creates a pipe end which has a wall of gradually decreasing thickness toward the extreme end of the pipe. This end of the 60 pipe is then slit up through and beyond the beveled surface 2, as shown by 4, Figs. 2 and 3, to form a plurality of separable members 5, as plainly shown in Figs. 2 and 4. These slits 4, as denoted by their name, 65 are of no substantial width so that there is no loss of material caused in the pipe section by their formation, which such loss of material, if it occurred and were substantial, would result in the members 5 breaking 70 off or spreading too easily when the post is driven into its foundation. The improved post thus formed is then driven or otherwise forced into the post foundation, during which driving action the compacted 75 weight of earth within the comparatively broad long bevel cutting edge 6, Fig. 1, which tends to be forced into the restricted aperture 7, Fig. 1, at a certain depth spreads the separable members 5 in the manner 80 shown in Fig. 3. The driving of the post to a desired depth effects such a material spreading of said members 5 that the distance between two diametrically opposite members may become two or more times as 85 great as the distance between them before the post is driven into the foundation and thus the post is set with a very firm anchorage.

What I claim is:

1. An improved fence post consisting of a section of integral, continuous metallic pipe of substantially uniform exterior diameter, interiorly beveled at one end to form a long-sloping cutting edge, said end 95 being slit to form a plurality of separable members whose contiguous side edges substantially contact with each other.

2. An improved fence post consisting of a section of integral, continuous metallic 100 pipe of substantially uniform exterior diameter formed at one end into a plurality

of separable members, the aggregate length of whose end edges is substantially equal to the circumference of the pipe, said pipe end being reamed out on a long bevel to 5 form a wall of gradually decreasing thickness toward the extreme end of the pipe.

In testimony whereof, I have signed this

specification on this 30th day of August, 1916.

GEORGE C. SHARPE.
